UNITED STATES PATENT OFFICE.

WILLIAM C. NORCROSS, OF TERRE HAUTE, INDIANA, ASSIGNOR TO AMERICAN MOLDING MACHINE CO., OF TERRE HAUTE, INDIANA, A CORPORATION OF INDIANA.

COMBINATION JOLT-RAMMING AND STRIPPING MACHINE.

1,274,752.

Specification of Letters Patent. Patented Aug. 6, 1918.

Application filed August 30, 1917. Serial No. 188,895.

To all whom it may concern:

Be it known that I, WILLIAM C. NORCROSS, a citizen of the United States, residing at Terre Haute, county of Vigo, and State of Indiana, have invented certain new and useful Improvements in Combination Jolt-Ramming and Stripping Machines, of which the following is a specification.

This invention relates to those molding machines which are adapted to ram the mold by jolting action and to draw and strip the pattern from the rammed mold.

One of the objects of my invention is to provide a novel arrangement and combination of jolting table, flask support, and stripping means, such as stripping posts, carried by the jolting table and arranged for utilization to support the flask so that the pattern may be drawn and stripped from the rammed mold by the descent of the table. My improvement entirely dispenses with the necessity for rocking the mold over preparatory to drawing the pattern, or, using auxiliary cylinders or means for operating the stripping posts such as have heretofore been proposed.

In carrying out the foregoing object, I employ stripping posts carried by the jolting table, a stripping plate which supports the flask, and means which may be arranged to support the posts so that they will hold the stripping plate and flask in elevated position, to permit the table and pattern to be lowered in relation to the aforesaid parts, thereby drawing the pattern and stripping it.

Another object is to provide stripping posts, carried by the jolting table, which can be shifted quickly to accommodate the flasks and stripping plates of different sizes, for the purpose of effecting the drawing and stripping of any pattern which may be used.

A still further object is the provision of improved abutment or supporting means for the stripping posts and for guarding them to prevent access of sand thereto.

A further object is to provide, in a jolt-ramming pattern drawing and stripping machine, means adapted to start the table and pattern to draw from the mold so that if the gravitational action is insufficient to overcome the friction between the pattern and the mold, said means will start the draw.

The embodiment of the invention which is hereinafter set forth is to be considered as illustrative, rather than restrictive, of the scope of the invention, as modifications may be resorted to without departing from the principles of the invention.

In the accompanying drawings:

Figure 1 is a vertical section, certain parts being in full lines, showing the piston and table down and mold rammed;

Fig. 2 is a section on line 2-2, Fig. 1, showing the arrangement of stripping post supports and their operating means;

Fig. 3 is a view similar to Fig. 1, showing the flask and mold supported in elevated position by the stripping posts, the table and pattern having partially descended, after the drawing of the pattern from the mold; and

Figs. 4 and 5 are detail sections on lines 4-4 and 5-5 respectively of Fig. 3.

The base 1 supports a cylinder 2 in which is a piston 3 having a valve 4 which controls the up and down jolting of the piston, the valve being adapted to strike the pins 5 to prevent it from locking below its normal position as shown in Fig. 1. A pipe 6 having valve 7 admits suitable air pressure for the elevation of the piston, with its load, and a pipe 8 provided with valve 9, lets off the exhaust. There being provided an opening 10 in the bottom of the piston 3, it is unnecessary to provide the separate air supply pipe 11 having three-way valve 12 but this may be employed, for convenience of operation, if desired, in elevating the piston to the stripping position and in controlling the descent of the piston in drawing mold.

The valve 4 is set forth and claimed in another application executed of even date herewith; it is not necessary to use said valve in connection with my present improvements as the valve may be used on any jolt-ramming machine and is particularly adapted for use on machines having cylinders of small diameter where valves such as shown in my Patents 1,031,084; 1,194,059; 1,231,187; 1,224,407; and application Serial No. 126,846, filed October 21, 1916, are not well adapted for use.

The jolt table 13 is carried by the head of piston 3, as in my earlier machines. Carried by the head of piston 3 is a guide pin 14 operating in a guide 15 for the purpose

of preventing the piston from turning. The piston also carries a stop bolt 16 which slides through an opening in the flange or head 17 of the cylinder 2 and carries a sleeve 18 which rests on a washer and nut 19 and contains a coil spring 20 whose upper end projects above the cup. The spring 20 is adapted to engage the head 17 to cushion the extreme upward movement of the piston, 5 until the end of the sleeve or cup engages the head 17, thereby arresting the piston. The spring is then under compression and when the flask, mold, and stripping plate have been supported as shown in Fig. 3, 10 preparatory to descent of the piston to draw, if the gravitational action is insufficient, the expansion of the spring 20 will start the draw. In Fig. 3 the pattern has been substantially drawn and the spring 20 has descended so 15 that it is out of contact with the head 17.

The safety bolt and stop just described is substantially similar to that set forth in my application for combination jolt-ramming and rock-over machine, Serial No. 185,471, 20 filed August 10, 1917, but in the present invention, the safety bolt serves a different function than served in the machine of the said application.

Rising from the base 1 are tubular housings 21. Three or more of the housings will 30 be used, according to the size of the machine. Preferably, four housings are employed, the number being dependent on the shape of the stripping plate which is shown at 22. 35 Usually, the stripping plate 22 is rectangular and there are four housings 21 arranged below the table 13 in line with the four corners of the plate 22. In any instance, the number of housings is determined by the 40 number of the stripping posts 23 which are employed, these being dependent in turn, upon the shape of the stripping plate. The housings 21 are adapted to freely receive the stripping posts 23 except when the stripping 45 posts are supported in the manner shown in Fig. 3. The table 13 is provided with vertical openings 24 in any of which the stripping posts 23 may be dropped, the heads 25 of the stripping posts normally lying in 50 countersinks 26 in the upper face of the table 13. By disposing the stripping posts 23 in one set of the openings 24, the stripping posts are adapted to support a given size of stripping plate 22 and by placing the posts 55 in other openings 24, the posts are adapted to support another size of stripping plate 22. The housings 21, being of the flattened tubular shape shown in Fig. 5, they are adapted to receive the stripping posts 23 whether the 60 latter are located in the inner openings 24 or in the outer openings 24. The stripping posts 23 being loosely carried by the holes 24, they can be quickly lifted out of one set of holes and placed in another set; they are 65 also free to slide in the holes, or to have the

table slide in relation to them when the pattern is being drawn as shown in Fig. 3.

The heads 27 of the housings 21 have openings 28 in line with the openings 24, 24^a, for the reception of the stripping posts 23. 70 The posts are thus guided into the housings and, in addition, sand is prevented from getting into the housings.

Pivoted at 29 to the heads 27 are supports 30 for covering or closing the heads 27 when 75 the posts 23 are to be supported as shown in Figs. 3 and 4, said supports then covering the openings 28. The supports 30 may be coupled in pairs by pull rods 31.

The flask 32 is supported by the stripping 80 plate 22 and secured thereto by dowels 33; trunnions 34 may be provided on the flask to enable the flask to be lifted off, or, if the flask is light enough, it may have handles to be directly grasped by the operators. 85

The flask may have bars 35 to assist in carrying the sand 36.

The pattern 37 is secured to the table 13 by lag screws 38. The stripping plate 22 conforms to the contour of the pattern 37, 90 as usual.

Operation: The pattern 37 is first secured to the table 13 and the stripping plate 22 placed around it and on the table. The flask 32 is then placed on the stripping plate 22 and secured by dowel pins 33. The sand 36 is then filled into the flask. Having opened the valves 8 and 9, the piston 3 rapidly jolts or vibrates the table 13 up and down, thus ramming or packing the sand 100 around the pattern and forming the mold. The valve 9 is now closed. If the pipe 11 and valve 12 are used, the valve 7 will be closed but pipe 11 and valve 12 need not be used and if they are omitted, the elevation 105 of the piston will be controlled by valve 7. Air is admitted, causing the piston to rise to its extreme height, carrying up the table 13, stripping posts 23, stripping plate 22, flask 32, and pattern 37. After the lower 110 ends of the stripping posts 23 have cleared the tops of the housings 21, the pull bars 31 are shifted to dispose the supports 30 over the heads 27. The air is then released from the cylinder by closing valve 7 and opening 115 valve 12 (or valve 9, if pipe 11 is not provided), whereupon the lower ends of the stripping posts 23 rest upon the supports 30. If the weight carried by the piston is not sufficient to draw the pattern out of the 120 mold, the spring 20 assists in starting the pattern; thereafter, the table and pattern descend by gravity with the piston, the stripping plate 22, flask and mold being supported as shown in Fig. 3, until the pattern 125 is drawn and the table has returned to normal position. The flask and mold may now be lifted by a crane or by hand from the stripping plate. Thereafter, the piston is run up again to its extreme height and the 130

supports 30 are swung to the position shown in Fig. 2 and the table is then lowered to normal position.

In my invention, the stripping posts are carried by the table 13 and may be placed inwardly, or outwardly to accommodate the stripping plates and flasks of different sizes, all extraneous means for operating the stripping posts, as previously proposed in the art, being done away with.

Having thus described my invention, what I claim as new and desire to secure by Letters Patent, is:—

1. In a combination jolt-ramming and stripping machine, a table, means for jolting the table and for elevating it, said table being adapted to carry the pattern and the flask, and means carried by and raised with the table adapted for being freed from the table and utilized for supporting the flask while the table is descending to draw the pattern from the mold.

2. In a combination jolt-ramming and stripping machine, a table, means for jolting the table and for elevating it, said table being adapted to carry the pattern and the flask, stripping posts carried by the table and adapted to be raised thereby which are adapted to be freed therefrom so that the table may move in relation thereto, and means for holding the stripping posts while permitting descent of the table, whereby the stripping posts are adapted to support the flask and mold when the pattern is being drawn by the descent of the table.

3. In a combination jolt-ramming and stripping machine, a table, means for jolting the table and for elevating it, said table being adapted to carry the pattern and the flask, stripping posts loosely or slidably related to the table and suspended and carried thereby, and supporting means, whereby said posts are rendered adaptable to support the flask and mold on the descent of the table and pattern.

4. In a combination jolt-ramming and stripping machine, a table, means for jolting the table and for elevating it, said table being adapted to carry the pattern and the flask, and flask supporting stripping posts carried by and raised with the table and adapted to be shifted laterally to different points thereof to accommodate flasks of different sizes, said table being movable up and down in relation to said posts.

5. In a combination jolt-ramming and stripping machine, a table, means for jolting

the table and for elevating it, said table being adapted to carry the pattern and the flask, said table having vertical openings disposed at different points thereof, and stripping posts slidably and removably arranged in said openings and adapted to be shifted from one set of openings to another set to accommodate flasks of different sizes.

6. In a combination jolt-ramming and stripping machine, a table, means for jolting the table and for elevating it, said table being adapted to carry the pattern and the flask, upright housings, shiftable supports carried by said housings, and stripping posts slidably related to the table and carried thereby which are adapted to enter the housings when the supports are moved out of the way, said supports being adapted to be arranged to engage the stripping posts whereby the posts are adapted to support the flask and mold when the pattern is being drawn by the descent of the table.

7. In a combination jolt-ramming and stripping machine, a table, means for jolting the table and for elevating it, said table being adapted to carry the pattern and the flask, upright housings, stripping posts slidably and removably carried by the table and adapted to be changed from one position to another on said table to accommodate flasks of different sizes, said posts being arranged so that they will enter the housings when in their different set positions, and means carried by the housings adapted to be arranged to engage and support the posts so that the flask will be supported when the pattern is being drawn by the descent of the table.

8. In a combination jolt-ramming and stripping machine, a table, means for jolting the table and for elevating it, said table being adapted to carry the flask, stripping posts loosely carried by and raised with said table for supporting the flask independently of the table when the table descends, and a combined spring cushion and stop carried by the table and arranged so that the spring cushion is first placed under compression before the stop arrests the extreme elevation of the table, whereby the spring cushion serves as an auxiliary means for starting the draw when the table descends.

In testimony whereof, I hereunto affix my signature.

WILLIAM C. NORCROSS.
